Patented Mar. 15, 1921.

2 SHEETS—SHEET 2.

UNITED STATES PATENT OFFICE.

WILLIAM H. BARTELL AND HENRY C. LOESCH, OF COLORADO SPRINGS, COLORADO.

ROAD-DRAG.

1,371,839.

Specification of Letters Patent. Patented Mar. 15, 1921.

Application filed October 23, 1917. Serial No. 198,055.

To all whom it may concern:

Be it known that we, WILLIAM H. BARTELL and HENRY C. LOESCH, citizens of the United States, residing at Colorado Springs, in the 5 county of El Paso and State of Colorado, have invented certain new and useful Improvements in Road-Drags, of which the following is a specification.

This invention relates to new and useful 10 improvements in road drags, and the primary object of the invention is to provide a road drag of this character, provided with means whereby the drag bars may be capable of various adjustments as is obvious.

15 Another object of the invention is to provide a road drag of this character, formed of oppositely disposed scraper sections, provided with reversible angularly adjustable drag bars, said sections being capable of 20 various adjustments with respect to each other, either to scrape the dirt toward the center of the road, or to either side thereof.

A further object of the invention is to 25 provide a device of this character, which is easily and simply constructed, inexpensive to manufacture, and one which will be very efficient in operation.

With these and numerous other objects in 30 view, our invention consists of the novel features of construction, combination and arrangement of parts which will be herein referred to, and more particularly pointed out in the specification and claim.

In the accompanying drawings:

35 Figure 1 is a top plan view of the road drag;

Fig. 2 is an end elevation thereof;

Fig. 3 is a detail perspective view of one 40 of the connecting means between the drag bars, and connecting rods; and

Fig. 4 are diagrammatic views of various positions in which the scraper sections may be placed.

In describing our invention, we shall refer 45 to the drawings in which similar reference characters designate corresponding parts throughout the several views.

The drag is formed of two scraper sections 50 designated by the numerals 1 and 2, which are each formed of a plurality of parallel drag bars 3. The scraper section 1 has the parallel drag bars 3 connected intermediate, the ends of the same by spaced parallel connecting rods 4, preferably formed of angle iron, and end connecting rods 5, which are 55 bent, as clearly shown in Fig. 1 of the draw-

ings. These connecting rods form a frame that is arranged above the drag bars 3, and each of the drag bars 3 has secured to the rear sides thereof, an angle iron designated 60 by the numeral 6, which has secured to the upper surface thereof upwardly projecting arms 7 having their upper ends pivoted as shown at 8 to the connecting rods 4 and 5. By this connection, the drag bars, are adapted 65 to rock, when the rocking means are applied as will be hereinafter more fully described. The opposite parallel connecting rods 4 are connected with the end connecting rods 5, by cross connected link members 9 70 and 10.

Projecting upwardly between the spaced connecting rods 4, that are centrally disposed with respect to the scraper section 1, are arms 11, having feet 12 on their lower 75 ends secured to the angle iron 6, said arms 11 extending above the arms 8, and having their upper ends connected by a transversely extending bar 12'. The bar 12' has its rear extremity connected to a pivoted lever 13 80 mounted on the tapered section, said lever being adapted to be locked in various adjusted positions by means of an arcuate rack member 14, provided with a plurality of apertures, adapted for alinement with an 85 aperture through the lever, a pin insertible therethrough to hold the lever in various adjusted positions. The rack 14 is secured in position on the rear end of the scraper section 1, by projecting arms 15, as clearly 90 shown in Fig. 2 of the drawings.

The scraper section 2 is substantially similar to the section 1, except that the center connecting rods which are designated by the numeral 16 are curved to conform to the 95 curvature of the outer connecting rods 17. The lever and locking means associated therewith are similar to the means employed on the sections 1, and additional description thereof and the other parts of this scraper section are unnecessary. The operation of adjusting the rack bars of the two section is exactly similar.

The sections are connected by an adjustable link 18, and the scraper sections 1 and 2 105 are capable of various adjustments as shown in Fig. 4 of the drawings so that the dirt scraped thereby may be directed toward the center of the road, on each side thereof or to one side as desired. The opposite ends 110 of the sections are provided with draft means 19, that receive chains, which are connected

with the power used to pull the drag and by varying the length of the chains the various adjustments suggested in Fig. 4 may be obtained, the link 18 maintaining the 5 sections in properly spaced relation.

In operation, the drag bars 3 are normally disposed upright, as shown in Figs. 1 and 2 of the drawings, when it is desired to shift the same, the locking pin that locks the lever 10 to the rack 14 is removed, and the lever 13 swung in either direction. This will rock the bars 3, as the same are connected by the bar 12, arms 11, and angle iron 6 to the drag bars.

When the desired adjustment has been 15 made, the lever 13, is locked in position, by inserting the locking pin through the alining apertures, and the drag bars will be locked in various angularly adjusted positions. The 20 connected rods 4 and 5, and 16 and 17 of the sections, are held rigid, above the swingable bars 3, and the draft connections of the device are made to these frames.

From the above description taken in connection 25 with the accompanying drawings, it is thought that a clear and comprehensive understanding of the construction, operation, and advantages of our invention may be had, and while we have shown and described the device as embodying a specific 30

structure, we desire that it be understood that such changes may be made in said structure as do not depart from the spirit and scope of the invention as claimed.

Having fully described our invention 35 what we claim as new, and desire to secure by Letters Patent is:

In a road drag, scraper sections, said sections comprising a plurality of parallel scraper bars, angle bars connected to the 40 scraper bars, upstanding arms rigidly connected with the angle bars, angularly bent connecting rods connecting the upper terminals of said arms, relatively long arms connected medially with the angle bars, two of 45 said angularly bent connecting rods being arranged on opposite sides of the relatively long arms, said sections being movable into alinement or various angular positions, an adjustable spacing member connecting the 50 inner angularly bent connecting rods in proximity to the rear scraper bars, and flexible draft members connected with the opposite terminals of each section for angling or straightening the sections by the pull of the 55 draft animals.

In testimony whereof, we affix our signatures hereto.

WILLIAM H. BARTELL.
HENRY C. LOESCH.
